UNITED STATES PATENT OFFICE.

JOHN R. VAN DYNE, OF SEDALIA, MISSOURI.

DISINFECTING APPARATUS.

1,139,740.

Specification of Letters Patent. Patented May 18, 1915.

Application filed April 23, 1912, Serial No. 692,650. Renewed October 26, 1914. Serial No. 868,740.

To all whom it may concern:

Be it known that I, JOHN R. VAN DYNE, a citizen of the United States, residing at Sedalia, in the county of Pettis and State of Missouri, have invented certain new and useful Improvements in Disinfecting Apparatus, of which the following is a specification.

This invention relates to apparatus for gradually and continuously feeding disinfecting liquid to places where it is required.

The present invention relates particularly to apparatus of the type shown in my prior Patents No. 893,208, dated July 14, 1908 and No. 931,817, dated August 24, 1909.

The primary object of the invention is to provide disinfecting apparatus for use on railway trains, steamboats and the like, so designed that the disinfecting liquid will be fed only when the conveyance is in motion, thereby preventing the waste of disinfectant when it is not needed, as, for example, when a car is standing idle upon a siding.

With the above and other objects in view, the invention consists in the construction and arrangement of parts hereinafter described and illustrated in the accompanying drawings, in which,

Figure 1 is a central vertical section through my improved apparatus; Fig. 2 is an inverted plan view thereof, parts being in section, on the line 2—2 of Fig. 1; and, Fig. 3 is a vertical section on the line 3—3 of Fig. 2.

Referring to the drawings in detail, my improved apparatus comprises a container which is made up of two sections 1 and 7, detachably connected, and held together by the frictional engagement of the upper part 40 of the section 7 with the flange 1^a at the lower part of the section 1. A screw top 2 is provided through which the apparatus may be filled with a suitable disinfecting liquid. A transverse partition 3 divides the 45 container into upper and lower compartments, and depending centrally from this partition is a concentrically disposed cylindrical extension 4 which lies within the lower section or cup 7. The extension 4 is 50 provided with a bottom 5 having a central opening constituting a valve seat, such opening being preferably protected by a wire gauze screen 8, as in my prior Patent No. 931,817 above referred to. A conical 55 valve 9 co-operates with the above mentioned seat, and is carried by a float 10 made of

cork or similar material. It is obvious without further discussion that this float valve serves to maintain a constant liquid level in the cup 7 at a height approximately 60 as shown in Fig. 1. The float 10 is prevented from falling away by means of a yoke 11, and is surrounded by a guard ring 12 of the same diameter as the extension 4.

In the upper part of the cup 7 are 65 formed a plurality of openings 7^a through which disinfecting vapors may escape into the air. In order to facilitate the dissemination of such vapors a wick 6 dips into the liquid in the cup 7 and surrounds the extension 4 and ring 12, as clearly shown in the drawing.

The above described construction of container is simple and practical and obviates the necessity for inner and outer casings as 75 heretofore employed.

Rigidly secured to the bottom of the cup 7 is a tube 13 which is preferably vertically arranged and which has, at its lower end an opening 14 to permit the entrance of liquid. 80 Within the tube 13 is adapted to telescope a tube 15, having at its upper end an annular enlargement or shoulder 16 adapted to engage the upper edge of the tube 13. Enclosed within the tube 15 is one end of a 85 siphon wick 17, the other end of which is inserted in the usual delivery pipe 18 which is also rigidly secured to the bottom of the cup 7 and which communicates with the usual discharge nipple 19. The tubes 13 and 90 18 are rigidly united at their upper ends by the brace 20, and, as clearly shown in Fig. 2, are disposed in the annular space between the extension 4 and the walls of the cup 7. The tube 15 is open at its lower end but is 95 provided with a cross bar or pin 15^a which prevents the wick 17 from projecting through or beyond the lower end of the tube.

In practice the liquid level is indicated by 100 the line α , and the length of the tube 15 is such that its lower end will lie at a point just above such liquid level, further downward movement being prevented by virtue of the engagement of the annular shoulder 105 16 with the upper edge of the tube 13. Under these conditions, when the apparatus is at rest it will be seen that the wick 17 is out of contact with the liquid and therefore does not feed any disinfectant into the delivery 110 tube. As soon, however, as the apparatus is subjected to the irregular movement or jolt-

ing of a conveyance, such as a railway car, such movement produces agitation of the liquid in the tube 13 and causes the same to slosh upwardly so as to impregnate the wick 17. As long as the car is running such agitation continues and the continuous wetting of the lower end of the wick causes the liquid to permeate therethrough and be discharged from the delivery nipple in the usual way, 10 the float valve serving to admit more liquid to the cup as it is used up. Immediately however that the vehicle stops and the agitation ceases, the feeding of the disinfectant is discontinued, for the reason that the wick is above the normal liquid level in the tube. It will thus be seen that by the employment of my improved apparatus a great saving can be effected in the use of disinfectants without sacrificing any of the advantages of 20 the usual apparatus, and it will further be observed that the feeding of the disinfectant is begun and stopped entirely automatically without any attention on the part of the employees.

25 What I claim is:—

1. A disinfectant container comprising a cylindrical body having at one end a cylindrical extension of less diameter than said body and at the other end an opening 30 through which it may be filled, an open top cup of substantially the same diameter as said body wholly inclosing said extension, the edges of said cup and body being in frictional engagement, means controlled by the liquid level in said cup for governing 35 the flow of liquid from said extension into the cup, whereby a substantially constant level in said cup is maintained, a delivery tube opening through the bottom of said cup, and disposed within the annular space 40 between said extension and the sides of said cup, and a siphon wick in said tube.

2. Disinfecting apparatus comprising a

liquid container, means for maintaining a constant normal liquid level in said container, and a delivery wick supported at such a height that its end is just above such normal level.

3. Disinfecting apparatus comprising a liquid container, a delivery tube carried thereby, a siphon wick having one end lying in said tube, a second tube also supported by said container and having an opening to admit liquid, the other end of said wick being inclosed in said second tube, and means for limiting the extent to which the wick may be inserted in such tube.

4. Disinfecting apparatus comprising a liquid container, a vertical delivery tube carried thereby, a second tube in fixed spaced 60 relation to the first and having an opening adjacent the bottom of said container, a third tube, open at both ends, and adapted to telescope within said second tube, a siphon wick having one end inserted in said delivery tube and the other end inclosed within said third tube, and an annular shoulder on such third tube adapted to engage the edge of the second named tube and limit 65 the movement of the third tube and wick relative thereto.

5. Disinfecting apparatus comprising a liquid container, a delivery tube carried thereby, a wick in said delivery tube, and means normally maintaining said wick out 75 of contact with the liquid when said container is at rest, said wick being so positioned as to be impregnated whenever the container is jolted.

In testimony whereof I affix my signature 80 in presence of two witnesses.

JOHN R. VAN DYNE.
